B SCHVERMA

UNITED STATES PATENT OFFICE.

BOHUMIL SCHVERMA, OF TWO RIVERS, WISCONSIN.

EGG-CARRIER.

1,140,005.

Specification of Letters Patent. Patented May 18, 1915.

Application filed May 2, 1914. Serial No. 836,015.

To all whom it may concern:

Be it known that I, BOHUMIL SCHVERMA, a citizen of the United States, residing at Two Rivers, in the county of Manitowoc 5 and State of Wisconsin, have invented certain new and useful Improvements in Egg-Carriers, of which the following is a specification, reference being had to the accompanying drawings.

10 This invention relates to new and useful improvements in shipping receptacles and more particularly to what will be hereinafter known as a sectional egg carrier, the main object of the present invention being the 15 provision of a device of this character wherein eggs can be conveniently shipped by express, parcel post or freight, without becoming broken during transportation.

Another object of the present invention 20 is the provision of an egg carrier which is formed of a number of sections, each section being provided with means whereby a number of the sections may be readily secured together during transportation in such a 25 manner that any shock or jar conveyed to the sections will not be communicated to the eggs, within the carrier and are so arranged that they may be readily connected together or disconnected.

30 Another object of the present invention is the provision of an egg carrier of the above character which will possess advantages in points of efficiency and durability, is inexpensive to manufacture and, at the same 35 time, is simple in construction and operation.

With the above and other objects in view, the invention consists in the novel features 40 of construction, combination and arrangement of parts as will be hereinafter referred to and more particularly pointed out in the specification and claims.

In the accompanying drawings forming a 45 part of this application, Figure 1 is a front elevation of an egg carrier constructed in accordance with my invention, parts thereof being broken away and illustrated in cross-section. Fig. 2 is a side elevation illustrating the cover in a partly raised position, 50 parts thereof being broken away and shown in cross section. Fig. 3 is a top plan view illustrating the interior of the sections; and Fig. 4 is a transverse sectional view of one 55 of the frame members.

In Fig. 1, I have illustrated one of the

sections of my improved carrier which comprises a plurality of compartment members generally indicated by the numeral 1, which include a substantially rectangular frame 2, closed at each side by means of the layers 60 of screen wire 3, having formed therein a plurality of aligned openings 4. Extending inwardly from each side of these openings 4, are the supporting straps 5 which extend transversely across the openings in opposite 65 directions to form a suitable pocket for the reception of one end of the egg. It will be noted that in forming the openings 4 within each side wall of the frame, they are so arranged that the openings formed in one side 70 will be disposed between or out of alignment with the openings upon the other side thereof, this feature being clearly illustrated in Fig. 3.

In forming the sections of my egg carrier, 75 the frames 2 are hingedly connected together by means of the hinges 6 and when arranged in super-posed relation are securely retained against any lateral movement by means of the pins 7, carried by the frames 80 and arranged upon one face thereof and adapted to be arranged within the openings 8, formed in the adjacent face of an adjacent frame, so that when the frames are arranged in their operative positions, the lugs 7 will 85 be arranged within said openings. The frames of each of the sections are securely held in position by means of the hooks 9 which are adapted to engage with the eyes 10. From this it will be seen that in order 90 to fill each of the sections, the top frame members are thrown back and the lowermost frame member filled and after being filled, is covered by the second frame member 95 which is then filled and covered by the frame member next in order and so on, until all of the frames have been filled. After each frame member is filled, the hook members 9 are engaged with the eyes 10 carried by the frame above and so on until the entire frame 100 members have been filled and securely fastened together. The top frame of each of the sections is provided with a raised central portion 11 which when the sections are arranged in super-imposed relation, is 105 adapted to fit within the recessed bottom member 12, so as to prevent any lateral movement of the sections when arranged one above the other. The sections are further held against movement by means of the hook 110

members 13 which are adapted to engage with the eyes 14 in order to securely retain each section in its proper position. When it is desired to arrange the sections in alinement, the side bars 14' which are provided at one of their ends with a central lug 15 and at their other ends with a central opening 16, are to be arranged in alinement so that the lugs 15 will fit within the openings 16. The sections are then securely held against longitudinal movement by means of a latch plate 17 which is hingedly connected to one end of one of the bars 14, the latch plate 17 being provided at its other end with an elongated opening 18 which is adapted to receive the upwardly projecting stud 19 fixed in the bar on which the latch plate 17 is mounted. It will be understood, from reference to Fig. 1 of the drawings, that the sections are assembled by engaging the stud 19 on the bar 14' carried by one section through the central opening in one of the bars 14' carried by an adjacent section. The plate 17 on the bar which is provided with a stud 19, is then swung over and downwardly so that the stud will be engaged through the opening in the latch plate. In this manner, any desired number of the sections may be connected together.

From the above description taken in connection with the accompanying drawings, it will be readily apparent that I have provided a simple and durable egg carrier, and means whereby a plurality of sections can be quickly and readily connected together and so arranged that any shock or jar conveyed to the same will not be imparted to the contents thereof. It will also be seen that each section includes a number of frames hingedly connected together and provided with the receiving pockets, said frames being securely connected together when in an effective position, in order to retain the eggs therein against any movement. It will also be apparent from the foregoing that I have provided a simple and durable egg carrier which is extremely simple in construction and can be manufac-

tured and placed upon the market at a comparatively low cost.

While I have shown and described the preferred form of my invention, it will be obvious that various changes in the details of construction and in the proportions may be resorted to for successfully carrying my invention into practice, without sacrificing any of the novel features or departing from the scope of the appended claims.

Having thus described this invention, what I claim is:

1. The combination of a plurality of article carriers each provided with parallel side bars, each bar having a socket in one end and a longitudinally projecting lug on its other end, shock absorbing springs arranged in the sockets, the lugs on the bars of one carrier being adapted to be fitted into the sockets on the bars of an adjacent carrier, a vertically disposed lug on one of the side bars of each carrier, the other side bar of each carrier being provided with an opening to receive the lug of the bar on an adjacent carrier, and latching devices on the latter bars to engage the lugs thereon.

2. The combination of a plurality of carriers each including a plurality of hingedly connected frames, said frames being provided with means for detachably connecting the same together at their free ends, side bars secured to one frame of each carrier each provided upon one end with a longitudinally projecting lug and in its other end with a socket, the lugs of the bars of one carrier being adapted for engagement in the sockets of the bar of an adjacent carrier, the side bars of the adjacent carriers being provided with additional means to hold the carriers against relative movement in one direction, and latch devices for connecting the several carriers to each other.

In testimony whereof I hereunto affix my signature in the presence of two witnesses.

BOHUMIL SCHVERMA.

Witnesses.
